UNITED STATES PATENT OFFICE.

JAMES DUNDAS WHITE, OF LONDON, ENGLAND.

PRINTING-TELEGRAPH RECEIVER.

SPECIFICATION forming part of Letters Patent No. 743,122, dated November 3, 1903.

Application filed January 3, 1903. Serial No. 137,721. (No model.)

To all whom it may concern:

Be it known that I, JAMES DUNDAS WHITE, a British subject, residing at 50 Clanricarde Gardens, London, England, have invented 5 new and useful Improvements in Printing-Telegraph Receivers, of which the following is a specification.

My improvements relate to printing-telegraph receivers of the class which print the characters in successive lines across a sheet of paper; and the objects of my invention are to provide a simple mechanism by which the characters are printed successively across the sheet without either the type or the paper being moved laterally and also a means whereby at the end of each line the paper is moved up ready for the new line. I shall describe the mechanism as operated by an electro-mechanical device, by which the rotation of 10 the type-cylinder is effected by currents of one polarity sent along a single wire, while the other cylinder is operated by currents of the other polarity sent along the same wire; but I do not limit the operation of the invention to this particular device. It may be also operated by any of the electromechanical devices used to rotate type-wheels and to effect printing, and a variation illustrating how one of these may be applied to it is also shown.

15 I attain my objects by the mechanism shown in the accompanying drawings, of which—

Figure 1 is a diagrammatic view of the apparatus as a whole; Fig. 2, a view from above 20 of the type-cylinder and the hammer-cylinder with the paper between them. Fig. 3 is a side view of the hammer-cylinder and its supporting-frame, taken from the side adjacent to the paper; and Figs. 4 and 5 are details of 25 modifications.

1 is the main wire, along which currents of either polarity may be sent from an ordinary transmitter. In this circuit is the electromagnet 2, which attracts the armature 3, and 30 the electromagnet 4, which attracts the armature 5. The armatures are so magnetized and the electromagnets so wound that a current of one polarity (which I shall call the "positive" current) causes the electromagnet 2 to attract the armature 3, but does not cause 35 the electromagnet 4 to attract the armature 5, while a current of the other polarity (which

I shall call the "negative" current) causes the electromagnet 4 to attract the armature 5, but does not cause the electromagnet 2 to attract the armature 3. These two electro-mechanical devices operate, respectively, the type-cylinder 6 and the hammer-cylinder 7, between which is arranged the paper 8.

The type-cylinder 6, which is preferably a 40 hollow cylinder of light metal, has along its surface a succession of longitudinal rows of type 9. The different rows (see Fig. 2) have different letters or characters; but throughout each separate longitudinal row the characters are the same, and every row has the same number of characters, that number being the same as the number of letter-spaces which it is intended to have in the line of print. This number may be as desired. In the accompanying drawings it is thirty-two. These rows of type are parallel to the axis of the cylinder, and they are placed around it one above another, so that they resemble a series of similar type-wheels similarly set along the 45 same axis with the letters of the alphabet progressing in regular order around the wheel. These rows of characters may be of any convenient number. In the drawings they are represented as twenty-eight, of which twenty-seven are occupied by the letters of the alphabet and one (marked 10) by the full stop, while the remaining row (marked 11) corresponds to spacing and is left blank. From the end of the cylinder in line with this blank 50 space projects an arm, which is bent around, as shown at 12, the bent part being sufficiently far out to allow it as the cylinder is revolved to pass clear of the hammer-cylinder 7 of the paper 8 and of the inking-cylinder 13, which latter is kept in position by its axle 14 playing in the slotted framework 15, and which inking-cylinder rests on the type-cylinder 6, inking it as it revolves.

The type-cylinder 6 is arranged so that it 55 can be revolved about its axis 16. Fitted on the end of it is the toothed wheel 17, which is actuated by the arm of a "push-and-pull" bifurcated lever 18, pivoted at 19 and having attached to it the armature 3. The two arms of this lever engage alternately the toothed wheel from opposite sides. As often as the electromagnet 2 attracts the armature the lever is pulled up, and as often as the magnet

ceases to operate the spring 20 causes the lever to return to the stop 21. Thus as often as the circuit 1 is closed by a positive current and opened again the arms of the lever alternately act upon the wheel. The proportions of the parts are such that successive double oscillations of this kind bring the successive rows of type 9 9 successively to the position indicated by the dotted line 22, which I shall call the "printing-level." By this step-by-step mechanism successive positive impulses serve to bring the required rows of characters to the printing-level.

The hammer-cylinder 7 is a light cylinder of about the same length as the other, having around it arranged as a single-turn spiral a series of projections 23 23, which I shall call the "hammers" or "impact-faces" and which are the same in number as the letters in any one of the longitudinal rows and which while set in a spiral correspond with the letters in breadth and in height and in lateral position. This cylinder 7 rests on an axle 24, journaled in the rocking frame 25, which latter is pivoted at 26 about a stationary center and has above it the extension 27, on which is located the armature 5. The general arrangement is such that as often as a negative current is sent along the line 1 the electromagnet 4 attracts the armature 5, so that the framework 25, carrying the hammer or impact-cylinder 7, is rocked about the center 26 against the type-cylinder 6, the paper 8 being between them. The parts of the cylinders which thus come into contact are of the hammer-cylinder, (the impact-face,) which is at the printing-level, and of the type-cylinder the opposite character of the row which is at that time at the printing-level. The rocking parts fall back when the current ceases, and the stop 28 prevents them falling back too far. Besides this rocking motion the cylinder 7 has a rotary movement on its axis, which is produced as follows: On the end of the cylinder 45 is the ratchet 29, which has as many teeth as there are hammer-faces on the cylinder. The stationary upright 30 carries a pawl 31, which engages in this ratchet, the proportions being such that when the hammer-cylinder falls back after each stroke the ratchet 29 (which is kept from reversing by the detent-pawl 32) is caught by the pawl 31 and moved around the space of one tooth, so that the impact-face which was at the printing-level is moved on and the face next below it is brought to the printing-level, ready for the next stroke. From the arrangement of the impact-faces it will be seen that this next face besides being below the other is on the right side of it, with the general result that as stroke after stroke is made the printing passes along from left to right and the last impact-face on the right is followed by the first on the left, thus beginning a new line. Thus the printing in the manner described is effected by negative pulsations through the wire 1, while the nature of the characters printed is determined by the

position of the type-cylinder 6 which is controlled by positive pulsations along the same wire.

The following arrangements are made for spacing: From the rocking frame 25 projects the arm 33, which moves with it, but which effects nothing except when the frame 25 is rocked against the type-cylinder 6 and the blank row 11 is at the printing-level. When that happens, the projection 33 comes against the projecting arm 12, and the proportions are such that this prevents the framework 25 and the hammer-cylinder 7 from coming as far as they otherwise would, but still allows them to come far enough for the return movement to cause the ratchet 29 to be caught and turned the space of a single tooth by the pawl 31, thus revolving the hammer-cylinder 85 as if a character had been struck and causing spacing without printing.

Before a new line of print is begun the paper must be spaced up for it, and the general arrangement of the paper may now be described. The paper 8, which is of a flexible character, is fed from the roll 34 around the roller 35, thence passes between the type-cylinder 6 and the hammer-cylinder 7, and is held between the small roller 36 and the large roller 37. On the end of that roller is a ratchet 38, actuated by a lever 39 through a pawl 40 and kept from reversing by another pawl 41. On one end of this lever is the armature 42, opposite which is the electromagnet 43 in the circuit 44, in which is the battery 45. As often as this local circuit is closed the electromagnet 43 attracts the armature 42, so that the lever 39 is moved, and the pawl 40 sends the ratchet 38, and so the roller 37, a step around, while as often as the circuit 44 is interrupted the magnet ceases to attract the armature, and the counterpoise 46 causes the lever 39 to return to the stop 47. The proportions are such that each step of the ratchet 110 sends the paper up sufficiently far for a new line of print to be begun. The arrangements for closing this circuit 44 at the right time are as follows: From the terminals 48 and 49 are suspended two light strips of metal 50 and 51, which are conductors of electricity. Normally they hang just clear of one another; but as often as the projection 52 on the end of the cylinder 7 (which projection is such as not to interfere with the rotation of the cylinder) comes to a certain place in the course of its rotation it encounters the strip 50, which it pushes against the strip 51, thus closing the circuit 44 and spacing up the paper. The projection 52 is so placed as to do this only when the frame 25 and the hammer-cylinder 7 fall back after the stroke in which the hammer on the extreme right of the cylinder has been at printing-level, so that the paper is spaced up between that stroke and the next stroke, which begins the new line.

I have described this invention as having the type-cylinder operated by currents of one polarity and the other cylinder as operated by

currents of the other polarity along the main wire; but, as already said, I do not limit the operation of the parts to this particular device. They may be operated also by any of the other electromechanical devices which are used in printing-telegraphs for rotating type-wheels and for operating the printing strokes. One of such alternative methods is shown in Fig. 4. In that figure the type-cylinder 6 is caused to rotate in the direction indicated by the arrow by a weight or clock-work or other means, while the number of steps to which it is rotated is governed by the escapement 53, which is pivoted as shown and engages on the ratchet 54, which is fixed on the end of the cylinder 6 and has half the number of teeth that the cylinder has faces. The lower end of the escapement has a magnetized armature 55, which is between the electromagnets 56 and 57 on the circuit 1, the general arrangement being that of a polarized relay and the operation being such that rapid reversals of polarity in that circuit oscillate the escapement and permit and control the step-by-step movement. The electromagnet 4 is slower in action than the magnets of the polarized relay, so that during the rapid changes of polarity it is ineffective; but as soon as the changes cease and the current flows continuously in either direction this magnet attracts the armature 5, thus operating the rocking movement, as already described. In this modification the armature 5 is not magnetized, but is a plain piece of soft iron.

The mechanism may also be operated by a two-wire system, in which case the intercepting-arms 12 and 33 may be eliminated. There may be no blank row on the type-cylinder, and spacing without printing may be effected, whatever row is at the printing-level. In such a system the circuit 1 is preferably used only to operate the type-cylinder, while, as shown in Fig. 5, the second circuit is used for the operations of the other cylinder. In this modification the upright 30, carrying the pawl 31, is fixed not rigidly, but on the pivot 58. Its range of movement is restricted by the stop 59, against which it is normally kept pressed by the spring 60, and on its lower end is the magnetized armature 61, opposite which is the electromagnet 62 in the second circuit 63. In the same circuit is the electromagnet 4, which attracts the magnetized armature 5, and so operates rocking, as already described. The armatures are so magnetized and the magnets so wound that as often as a current of the one polarity is sent through the circuit 63 the electromagnet 4 is caused to attract the armature 5, thus effecting printing followed by spacing, as already described; but the electromagnet 62 is not caused to attract the armature 61, while when a current of the other polarity is sent the electromagnet 4 is not caused to attract the armature 5; but the electromagnet 62 is caused to attract the armature 61, and the proportions are such that the

resulting movement of that upright and pawl send the ratchet and cylinder a step around, thus effecting spacing without printing.

I am aware that a stenographic and type-writing machine has been heretofore devised in which a sheet of paper passes between a series of anvil-faces progressing spirally around an axis and a series of straight-line printing-faces arranged like comb-teeth on the ends of depressible levers and adapted to advance and press the paper against an anvil-face along the spiral series as the latter is intermittently rotated, and I do not claim this principle of action.

In my invention a cylinder is provided with a series of alphabets and characters which progress around the cylinder and the letters and characters of which series are multiplied or repeated in parallel alignment with the axis, so that there is a straight series of similar letters or characters arranged in rows parallel to the axis, and another cylinder is arranged in parallel position to the first-named and bears a single spirally-progressing series of impact-faces on the other side of the paper, which cylinder is both intermittently rotated and moved bodily as a hammer to bring one of its impact-faces against the paper and the selected type-face of the other cylinder, the type-cylinder having an electrical step-by-step movement, so as to bring at will any portion of the type-cylinder to the printing-level and the hammer-cylinder having both a regular progressive step-by-step movement to bring each impact-face successively to the printing-level and having also an integral movement at right angles to its axis to deliver the printing blow, both said movements being effected by electromagnetic mechanism controlled by a circuit or circuits from a distant point, as hereinbefore described.

Having thus described my invention, what I claim as new, and desire to secure by Letters Patent, is—

1. An electromagnetic printing device, comprising a type-cylinder having circularly-arranged series of alphabets or characters disposed around the cylinder with each letter of each circular series repeated in rows parallel to the axis of the cylinder, a hammer-cylinder arranged parallel to the first-named cylinder and bearing a single row of spirally-arranged impact-faces, electromagnetic actuating devices for imparting to one cylinder a step-by-step rotary action and electromagnetic actuating devices for imparting to the other cylinder both a rotary step-by-step movement and an integral lateral movement to deliver the printing blow substantially as and for the purpose described.

2. An electromagnetic printing device, comprising a type-cylinder having circularly-arranged series of alphabets or characters disposed around the cylinder with each letter of each circular series repeated in rows parallel to the axis of the cylinder, a hammer-cylinder

der arranged parallel to the first-named cylinder and bearing a single row of spirally-arranged impact-faces, and electromagnetic actuating devices for both cylinders, the electromagnetic actuating device for one cylinder being constructed and arranged to be operated by a current of one polarity and that of the other cylinder being constructed and arranged to be operated by a current of the opposite polarity and the hammer-cylinder being arranged to move laterally to deliver the printing blow substantially as and for the purpose described.

3. An electromagnetic printing device comprising a type-cylinder having circularly-arranged series of alphabets or characters disposed around the cylinder with each letter of each circular series repeated in rows parallel to the axis of the cylinder, a hammer-cylinder arranged parallel to the first-named cylinder and bearing a single row of spirally-arranged impact-faces, electromagnetic actuating devices for both cylinders arranged to be operated by electric currents, the ham-

mer-cylinder being arranged to move laterally to deliver the printing blow, and electromagnetic feeding devices for the paper substantially as and for the purpose described.

4. An electromagnetic printing device comprising a type-cylinder having circularly-arranged series of alphabets or characters disposed around the cylinder with each letter of each circular series repeated in rows parallel to the axis of the cylinder, electromagnetic devices for actuating the cylinder with a step-by-step rotary movement, a hammer-cylinder arranged in movable bearings parallel to the first-named cylinder and bearing a single row of spirally-arranged impact-faces, and electromagnetic actuating devices for both 40 rotating this hammer-cylinder with a step-by-step movement and also projecting it bodily toward the other cylinder to deliver a printing blow substantially as described.
